(57) **CLAIM**

The ornamental design for a spray nozzle, as shown and described.

DESCRIPTION

FIG. 1 is a perspective view of the front and left side of the spray nozzle;

FIG. 2 is a bottom plan view of the spray nozzle;

FIG. 3 is an elevation view of the left side of the spray nozzle; and,

FIG. 4 is an elevation view of the front of the spray nozzle. The broken lines in the drawings depict environmental subject matter only and form no part of the claimed design.
